R. W. GERDEL

POWDER DISPENSER

Original Filed Oct. 1, 1923

FIG. 2

FIG. 4

FIG. 1

FIG. 3

INVENTOR.

Robert W. Gerdel

BY

Clark C. Mowd

ATTORNEY.

Patented May 4, 1926.

UNITED STATES PATENT OFFICE.

ROBERT W. GERDEL, OF EAST LANSING, MICHIGAN.

POWDER DISPENSER.

Application filed October 1, 1923, Serial No. 665,843. Renewed February 23, 1926.

To all whom it may concern:

Be it known that I, ROBERT W. GERDEL, a citizen of the United States, residing at East Lansing, in the county of Ingham and State of Michigan, have invented a new and useful Improvement in Powder Dispensers, of which the following is a specification.

My invention relates to devices for distributing powdered soap and similar articles in powdered form. Its purpose is to make a device that shall be simple in construction and reliable in operation, that shall keep the powdered material continually agitated and prevent from packing or clogging and that shall force out the desired amount at each operation.

I attain these purposes by the means shown in the accompanying drawings in which Fig. 1 is a vertical section of my device through the center. Fig. 2 is a plan view of the upper side of the shutoff slide, the section being taken on $x-x$. Fig. 3 is a plan view from the upper side showing the operation of the mechanism looking from section Y-Y and Fig. 4 is a detail showing the construction of the shutoff slide on section W-W.

In the drawings, 1 is the main body of my device, which may be of any approved form, construction, or material and is provided at the top with a filling opening 2. It is preferably adapted to be attached to the wall by a bracket 3. The bottom of the device is closed by a plate 4, provided with opening 5, which connects with a tube 18, and is closed by a shutoff slide 6 in which is an opening 7, above which is an inclined portion 8 of the slide 6. The slide 6, is attached to a shaft 9, which extends through the plate 4, and is provided with a stem 10, actuated by a link 11, and slide 12. An arm 16 is attached to the top of the shaft 9 and terminates in an agitator 17 which extends downward nearly to the plate 4. The slide is normally pressed outward by a spring 13, and when so pressed outward leaves the opening 5 closed by the shutoff slide 6. This position is shown by the full lines in Fig. 2. The slide 12 is provided with a stop 19 to limit its motion. When

the rod 12 is pushed in the slide 6 revolves and the opening 7 passes over the opening 5 and the inclined member 8 forces the required amount of soap down through the opening 5. The plate 6 then passes onward to the position shown by the dotted lines in Fig. 2 in which the opening 5 is again closed. As it retreats, however, the inclined member 8 operates in the reverse manner and carries the powdered soap away, so that little, if any more, will go through the opening. Fig. 4 illustrates the position of the parts at the moment the opening 7 is directly over the opening 5.

The space below the plate 4 is preferably closed by a plate 14 which is held in position by screws 15, passing through the plate into the plate 4.

I claim as my invention and desire to secure by Letters Patent:

1. In a device of the character described, in combination with a body adapted to hold a powdered substance and provided at the bottom with a plate having in it a distributing opening, a revoluble slide normally closing said opening, and provided with an opening adapted to pass over said distributing opening when said slide is revolved, and having an upwardly and forwardly inclined member extending over the opening in said slide, and means for revolving said slide so as to open and close said distributing opening.

2. In a device of the character described, in combination with a body adapted to hold a powdered substance and provided at the bottom with a plate having in it a distributing opening, a revoluble slide normally closing said opening, and provided with an opening adapted to pass over said distributing opening when said slide is revolved, and having an upwardly and forwardly inclined member extending over the opening in said slide, means for revolving said slide so as to open and close said distributing opening and an agitator in said body connected so as to revolve with said slide.

3. In a device of the character described, in combination with a body adapted to hold a powdered substance and provided at the

bottom with a plate having in it a distributing opening, a revoluble slide normally closing said opening; an opening adapted to pass over said distributing opening when said slide is revolved, and having an upwardly and forwardly inclined member extending over the opening in said slide;

means for revolving said slide so as to open and close said distributing opening; an agitator in said body connected so as to revolve 10 with said slide and a spring for retaining the said slide normally in the closed position.

ROBERT W. GERDEL.
